UNITED STATES PATENT OFFICE.

AUGUSTA S. JOHNSON, OF BROOKLYN, NEW YORK, ASSIGNOR TO MODEL BRASSIERE CO., INC., OF NEW YORK, N. Y., A CORPORATION OF NEW YORK.

BRASSIÈRE.

Application filed February 21, 1923. Serial No. 620,420.

To all whom it may concern:

Be it known that I, AUGUSTA S. JOHNSON, a subject of the King of Sweden, and resident of the borough of Brooklyn, county 5 of Kings, city and State of New York, have invented certain new and useful Improvements in Brassières, of which the following is a specification.

My invention relates to brassières and has 10 for its object to provide a garment of this type constructed in a novel manner to provide play and freedom when the person wearing the same is walking or sitting and to provide a perfect fit without discomfort 15 to said wearer. A further object is to construct the garment in a manner to provide a most effective diaphragm supporter. Other more specific objects of the invention will appear from the description hereinafter.

20 The accompanying drawing, without defining the limits of the invention, shows a face view of the garment embodying my improvements.

The garment is provided at the front with 25 duplicate sections 5 of suitable material preferably tapering upwardly and overlapping each other as shown, and each provided with downwardly tapering garter tabs 6 to the terminal ends of which garters 7 of any 30 customary and well-known type are secured. The sections 5 are arranged in opposed relations to each other so that the tapering garter tabs 6 project in opposite directions as illustrated. These tapering garter tabs are 35 loose relatively to each other while the sections 5 themselves are connected permanently along their edges with side gores 8 by stitching 9. The side gores 8 are cut to fit the sections 5 and terminate at their 40 upper edges in registry with the upper ends of the sections 5; the lower edges of said side gores are located at intermediate points of the sections 5 so that the tabs 6 thereof project downwardly beyond said side 45 gores 8 as shown. In the preferred construction the sections 5 are provided with a plurality of bones 10 which cross each other, for instance in the manner indicated in the drawing, to form a diaphragm section 11;

50 it will be understood that the number of bones 10 may be increased or decreased to meet the requirements of the particular garment or the judgment of the designer, said bones being located in the customary manner 55 in suitable pockets as shown. Additional

gores 12 and 13 are connected with the gores 8 and with each other respectively, the gores 13 at their free edges being provided with cooperating fastening devices 14 such as hooks and eyes, whereby the garment may 60 be detachably secured upon the wearer. The intermediate gores 12 are somewhat shorter than the gores 8 and 13 and at their lower edges are gathered, as indicated at 15, and connected with elastic inserts 16 which have 65 their opposite ends connected respectively with the gores 8 and 13; the inserts 16 are of such dimensions as to fill the spaces below the gores 12 and are arranged in the garment so as to be located below the waist 70 when the latter is worn. Shoulder bands 17 may form part of the garment if desired.

The garment when worn fits the wearer perfectly without discomfort, this being due 75 to the construction of the side and back gores of the garment in three sections and the provision of the elastic inserts at the lower ends of the gores 12 below the waist. Because of the presence of the bones 10 and 80 the diagonal arrangement thereof, a most effective diaphragm supporter which performs its functions in an efficient manner without discomfort to the wearer is provided. The garter tabs 6 extending one on 85 either side of the front panel in overlapping relations and being loose and separate from each other provide a maximum of play and freedom when the wearer is walking, sitting, exercising, etc., the double section 5 90 tapering upwardly as indicated add to the efficiency of the garment for its intended purposes. The garment provides an ideal two garter brassière which is designed to be worn with or without corset or girdle and 95 which provides a maximum of comfort with a maximum amount of efficiency as a retaining and supporting medium. The garment is secured upon the wearer in the customary manner by engaging the hooks and eyes 14 100 or their equivalent with each other at the back of the wearer.

Various changes in the specific form shown and described may be made within the scope of the claims without departing from 105 the spirit of the invention.

I claim:

1. A brassière comprising a plurality of connected gores, a double overlapping front section connected therewith and having ter- 110

5 minal tabs free and disconnected from each other, garters secured to the free ends of said terminal tabs and a plurality of bones in said double section intersecting each other in diagonal relations to form a diaphragm section.

10 2. A brassière comprising a double overlapping front section tapering upwardly and provided with terminal tabs free and disconnected from each other, garters secured to the terminal ends of said tabs, a plurality of gores connected with said front section and with each other and elastic inserts interposed between opposite pairs of 15 said gores and below corresponding gores on opposite sides of the garment.

16 3. A brassière comprising complemental gores spaced from each other, a front section located between and secured to said

20 complemental gores and tapering upwardly, said front section consisting of a double fabric having terminal tabs projecting beyond said gores in opposite directions, said tabs being free and disconnected from each other, garters attached to the terminal ends of said tabs, a plurality of bones located in said front section and intersecting each other in diagonal relations, intermediate gores connected with said first-named gores and being of less length than the same, additional 25 gores secured to said intermediate gores and projecting downwardly from the same and elastic inserts located between said first-named and said additional gores and being connected with each of said gores.

In testimony whereof I have hereby signed this specification.

AUGUSTA S. JOHNSON.
